UNITED STATES PATENT OFFICE

2,663,408

TYPOGRAPHICAL COMPOSING MACHINE

Richard Henry Scott, Hale, and Arthur Staniland
 Hayward, Altrincham, England, assignors to
 Linotype and Machinery Limited, London, Eng-
 land, a British company

Application September 1, 1950, Serial No. 182,706

17 Claims. (Cl. 199—45)

1

This invention relates to typographical composing machines of the kind known commercially under the registered trade-mark "Linotype," wherein circulating matrices are released from a channelled magazine in the order in which their characters are to appear in print and then assembled into line, the composed line transferred to the face of a slotted mould, the mould filled with molten metal to form a type bar or slug against the matrices which produce the type characters thereon, and the matrices thereafter elevated and returned through the medium of distributing mechanism to the channels in the magazine from which they started. More particularly, it relates to machines equipped with a plurality of magazines which may contain different matrix fonts, the magazines being adjustable columnwise to bring a selected magazine into operative position with respect to assembling and distributing mechanism.

To effect such columnwise adjustment of the magazines a manually operated lever connected through lever and link mechanism, or any similar mechanism, to a shift frame supporting the magazines, has been provided. Power-operated mechanism for effecting the columnwise adjustment of the magazines has been proposed, but such mechanism has comprised either means for bringing successive magazines into operative position or a reversible power drive operable independently of the machine drive.

According to the present invention, a typographical composing machine comprises a column of magazines which is adjustable to allow a selected magazine to be brought into operative position, a power drive operated by the machine drive or by an independent continuously rotatable drive for shifting said column of magazines and pre-selecting means for causing said power drive to bring any selected magazine of the column into operative position. There may be included means for connecting said power drive to the machine drive, and the pre-selecting means may be operative to disconnect the power drive upon the arrival of the selected magazine in operative position.

In carrying out the invention, the typographical composing machine comprises a column of magazines mounted on a bracket which is adjustable in opposite directions to bring a selected magazine into operative position, a power drive for moving said bracket in both directions, a device mounted on the bracket so as to be operable to disconnect the power drive, a number of adjustable members corresponding to the number of

2

magazines in the column and mounted on a fixed part of the machine, and means for moving any selected one of said members into the path of the device so as to operate the device and disconnect the power drive upon the arrival of the selected magazine in operative position. The adjustable members may be pivotally supported and a cam may be adjustable to pre-determined positions to rock a pre-selected member into the path of the disconnecting device.

A further feature of the invention consists in a typographical composing machine comprising a column of magazines which is adjustable to bring a selected magazine into operative position, a magazine locator member which is rotatable during adjustment of the magazines, a locator arm which is arranged to be engageable with said member at positions corresponding to the adjusted positions of the magazines, means for moving said arm out of engagement with the rotatable member to free the magazine column for adjustment, and means for moving the arm into engagement with the member at another position to hold the magazine column in adjusted position. Preferably the rotatable locator member comprising a pulley connected to a weight for counterbalancing the weight of the magazines and the locator arm is pivotally mounted on a fixed part of the machine adjacent said pulley. The locator arm may be so arranged that movement thereof out of engagement with the locator member actuates mechanism for connecting the magazine column to a power drive for shifting said column and movement of the locator arm into engagement with the locator member disconnects the power drive.

The invention will now be described by way of example with reference to the accompanying drawings in which:

40 Figure 1 is a side elevation of a portion of a typographical composing machine showing the power-operated mechanism for effecting columnwise adjustment of magazines according to the present invention;

45 Figure 2 is a rear sectional view taken on the line II—II of Figure 1;

Figure 3 is a side elevation of the control device for bringing the power-operated mechanism into operation;

Figure 4 is a rear view partly broken away and showing the magazine pre-selector mechanism;

Figure 5 is a front view of the pre-selector dial and hand control;

50 Figure 6 is a part plan view of the clutch control for the power-operated mechanism;

Figure 7 is a side elevation of a portion of a typographical composing machine showing an alternative form of mechanism for effecting a raising and lowering movement of the magazine column; and

Figure 8 is a rear sectional view taken on the line VIII—VIII of Figure 7.

Referring to Figure 1 of the drawings, a column of four magazines 1 (two only of which are shown) is arranged in an inclined position in a machine frame 2, and each magazine 1 is removably mounted on a base frame carried by a bracket or shift frame 3 which is movable in the machine frame 2 so as to bring any selected magazine or magazines of the column into operative position in relation to matrix assembling and distributing mechanisms (not shown). To counterbalance the weight of the bracket 3 and magazines 1, the bracket 3 is formed with a downward extension 4 which is slidable in a guide frame 5 secured to the machine frame. One end of a chain 6 is secured to the extension 4 and the other end of the chain is passed around and secured to a pulley 7, so tending to turn the pulley in a clockwise direction. The pulley 7 is provided with a hub 8 which is mounted on a shaft 9 carried by the machine frame and the hub 8 is integral with a pulley 10 having a larger diameter than the pulley 7. A second chain 11 is passed around and secured at one end to the pulley 10, the chain 11 being passed over a jockey pulley 12 and secured at the other end to a counter-balancing weight 13 which thus tends to turn the pulley in a counter-clockwise direction, in the manner set forth in the specification of Patent No. 2,605,838, dated August 5, 1952.

After the bracket 3 has been moved to bring a selected magazine into operative position in relation to the assembling and distributing mechanisms, the selected magazine is, according to the present invention, maintained and located in correct operative position by means of a recessed locator arm 14 (see Figure 3) which is brought into engagement with one of the locator studs L¹—L⁴ projecting from the side of the pulley 10. The number of locator studs (L¹—L⁴) on the pulley corresponds to the number of magazines in the column, and each locator stud is so arranged on the pulley that on rotation thereof the locator stud corresponding to the selected magazine is brought into correct position for engagement by the locator arm 14. The locator arm is pivotally mounted at 15 on the guide frame 5 and is provided with an extension 15^a connected by means of a flexible cable 16 to a hand-operated lever 17 for rendering power-operated mechanism active to bring a pre-selected magazine into operative position, as will now be more fully explained.

As is well known, the machine is provided with a power driven and constantly revolving intermediate shaft 18 (see Figures 1 to 3) from which certain organs of the machine are driven. In the present arrangement the driving portion 19 of a friction clutch is keyed to the intermediate shaft 18 so as to be rotatable therewith but movable axially therealong into and out of engagement with a driven portion 20 of the clutch which is freely mounted on the intermediate shaft 18. If preferred, the clutch 19, 20, may be mounted on an independent continuously rotatable shaft. The driven portion 20 of the clutch is integral with a worm 21 having a hub 22 which is freely mounted on the intermediate shaft 18 and supported in bearings 23, 24, forming part of a

bracket 25 fixed to the machine frame. The worm 21 meshes with a worm wheel 26 secured to a shaft 27 mounted in bearings 28, 29, in bracket 25, to which shaft 27 a profile cam 30 is secured. The profile cam 30 is engaged by a roller 31 mounted on a stud 32 on a cam lever 33 which is pivoted at 34 to the bracket 25. The cam lever 33 is adjustably connected by a link 35 to an arm 36 secured to a shaft 37 to which shaft is secured an arm 38 connected by a link 39 to the downward extension 4 of the bracket 3 on which the magazines are mounted. Thus, when the driving portion 19 of the friction clutch is brought into engagement with the driven portion 20, the profile cam 30 is rotated to raise or lower the column of magazines.

Operation of the clutch 19, 20, is effected by a lever 40 (see Figure 6) pivotally mounted at 41 in the machine frame and having at one end a fork 40^a engaging a groove 42 formed in the driving portion 19 of the clutch. An arm 43 secured to the lever 40 is connected to one end of a spring 44 which is secured at its other end to the machine frame, so as to pull the driving portion 19 of the clutch into engagement with the driven portion 20. An extension arm 45 pivotally connected to the lever 40 is connected to a toggle arm 46 which is pivotally connected at 47 to the other toggle arm 48^a pivoted at 48 to the machine frame. A link 49 is connected at one end to the pivot 47 and at its other end to the extension 15^a of the locator arm 14 (see Figure 3), the arrangement being such that movement of the locator arm 14 operates the toggle arms 46, 48^a, to effect engagement or disengagement of the clutch 19, 20. The locator arm 14 is held in engagement with a locator stud (L¹ or L², or L³ or L⁴) by means of a spring 50 and is disengaged from a stud against the action of spring 50 by operation of the hand lever 17. The locator arm 14 is held in such disengaged position by the engagement of a catch 51 thereon with a latch 52 and the clutch 19, 20, is held in engaged position (and hence the magazine column is moved) until the latch 52 is released by the magazine pre-selector mechanism now to be described.

The latch 52 is pivotally mounted at 53 (see Figure 4) on the guide frame 5, and rests on a stop peg 54. The latch 52 is provided with a setting screw 55 which is arranged to be engaged by the top end of a parallel motion bar 56 mounted on arms 57 pivoted at 58 to the guide frame 5. Movement of the parallel motion bar 56 is effected by the rocking of a triangular-shaped tumbler 59 carrying three rollers 60 and freely mounted on a stud 61 fixed to the extension 4 of the magazine supporting bracket 3. Mounted on the guide frame 5 and disposed between the upper and lower ends thereof are four interponents 62 (corresponding to the number of magazines in use) and any selected one of such interponents can be moved into the path of the tumbler 59 so as to rock the tumbler when the extension 4 (and hence the column of magazines) reaches a pre-selected position.

Each interponent 62 is freely suspended on a stud 63 secured to the guide frame 5 and is held out of the path of the tumbler 59 by a spring 64 secured at one end to the interponent and at the other end to the guide frame 5. Each interponent 62 is provided with a roller 65 which is held by its spring 64 against a slidable cam or selector bar 66 provided with four raised surfaces 67 (corresponding to the number of interponents 62).

Such surfaces 67 are so disposed on the bar 66 that movement of the selector bar 66 to pre-selected positions causes one of the raised surfaces 67 to engage a roller 65 on an interponent 62 and so move the selected interponent into the path of the tumbler 59.

The selector bar 66 is formed with a rack 67^a which is engaged by a spur pinion 68 secured to the end of a rotatable shaft 69 mounted in the guide frame 5. The other end of the shaft 69 has secured thereto a bevel gear 70 with which meshes a bevel gear 71 (see Figure 3) secured to one end of a rotatable shaft 72 mounted in bearings on the machine frame. The shaft 72 is provided at its other end with a pre-selector control handle 73 (see also Figure 5) having a spring-pressed detent 74 for engaging notches 75 in a graduated dial 76 on the machine frame.

To select a required magazine to be brought into operative position, the pre-selector control handle 73 is moved to the appropriate position on the dial 76 thereby moving the selector bar 66 to bring an interponent 62 into the path of the tumbler 59. The hand lever 17 is then operated to disengage the locator arm 14 from a locator stud (L¹ or L², or L³ or L⁴) the locator arm 14 being held in disengaged position by the latch 52. The movement of the locator arm 14 engages the friction clutch (19, 20) (as hereinbefore explained) so causing the downward extension 4 of the magazine supporting bracket 3 to be moved to a position in which the tumbler 59 thereon is rocked by the pre-selected interponent 62 so as to press against the parallel motion bar 56 and lift the end thereof into engagement with the screw 55. The consequent disengagement of the latch 52 from the catch 51 allows the spring 53 to move the locator arm 14, so disengaging the clutch 19, 20, and bringing the locator arm into engagement with another locator stud appropriate to the selected magazine.

In the modified construction shown in Figures 7 and 8, the profile cam 39 is replaced by a spiral gear 77 mounted on the shaft 21. The spiral gear 77 meshes with a spiral gear 78 mounted on a shaft 79 supported in bearings 80, 81, on the machine frame. A chain wheel 82 is loosely mounted on the shaft 79 and is connected by a chain 83 to a chain wheel 84 secured to the pulley 10. A gear wheel 85 is loosely mounted on the shaft 79 and meshes with a gear wheel 86 mounted on a short shaft 87 and secured to a chain wheel 88 which is connected by a chain 89 to a chain wheel 90 secured to the pulley 10.

A dog clutch 91 is slidably mounted on keys on the shaft 79 so as to be engageable on the one hand with teeth on the chain wheel 82 or to be engageable on the other hand with teeth on the gear wheel 85. Thus, if the clutch 19, 20, is engaged and the shaft 79 is driven in a counter-clockwise direction as viewed in Figure 7, the clutch 91, when engaged with the chain wheel 82, will rotate the pulley 10 in counter-clockwise direction and the magazine column will be lifted. If, however, the clutch 91 is engaged with the gear wheel 85 the gear wheel 86 and pulley 10 are driven in a clockwise direction so that the magazine column is lowered. Movement of the clutch 91 is effected by a forked lever 92 engaging a groove formed on the clutch 91, the lever 92 being mounted on a shaft 93 to which is connected an arm 94 provided with a roller 95 which engages between projections 96 on a slidable bar 97 mounted in guides on the machine frame. The slidable bar 97 is provided at its lower end

with a spring-loaded plunger 98 and at its upper end with a spring-loaded plunger 99, which plungers are engageable by a finger 100 protruding from the lower end of the extension 4.

When the extension 4 reaches the limit of its downward movement the finger 100 engages the plunger 98 and moves the slidable bar 97 to the position shown in Figures 7 and 8 in which the clutch 91 is engaged with the chain wheel 82 and the extension 4 and column of magazines can be lifted by the power-operated mechanism. When the extension 4 reaches the limit of its upward movement the finger 100 engages the plunger 99 and moves the slidable bar 97 to a position in which the clutch 91 is engaged with the gear wheel 85 and the extension 4 and magazine column can be lowered.

Having described our invention, we declare that what we claim and desire to secure by Letters Patent is:

1. A typographical composing machine comprising a column of magazines mounted on a bracket which is adjustable in opposite directions to bring a selected magazine into operative position, a power drive for moving the bracket in both directions, a clutch for connecting and disconnecting the magazine supporting bracket to and from the power drive, a tumbler mounted on the magazine supporting bracket, a parallel motion bar mounted on a fixed part of the machine and engageable by said tumbler for disconnecting said clutch, a plurality of adjustable members mounted on a fixed part of the machine, and means for moving any selected one of said members into the path of the tumbler so as to move the tumbler and parallel motion bar and disconnect the clutch from the power drive upon the arrival of the selected magazine in operative position.

2. A typographical composing machine comprising a column of magazines mounted on a bracket which is adjustable in opposite directions to bring a selected magazine into operative position, a power drive for moving the bracket in both directions, a clutch for connecting and disconnecting the magazine supporting bracket to and from the power drive, a tumbler mounted on the magazine supporting bracket, a parallel motion bar mounted on a fixed part of the machine and engageable by said tumbler for disconnecting said clutch, a plurality of adjustable members pivotally mounted on a fixed part of the machine, a cam for actuating said members, and means for adjusting the cam to predetermined positions to rock a pre-selected member into the path of the tumbler so as to move the tumbler and parallel motion bar and disconnect the clutch from the power drive upon the arrival of the selected magazine in operative position.

3. A typographical composing machine comprising a column of magazines, at least three in number, mounted on a bracket which is adjustable in opposite directions to bring a selected magazine into operative position, a uni-directional power drive, a cam which is rotatable in a single direction by said power drive, a cam lever connected to the magazine supporting bracket and operable by said cam for imparting a movement in opposite directions to the magazine column, a one-way clutch for connecting and disconnecting the rotatable cam to and from the power drive, a device mounted on the bracket and movable in opposite directions therewith and adapted to disengage the one-way clutch of the power drive in any adjusted position of the magazine column, a plurality of adjustable members

corresponding to the number of magazines in the column, said members being mounted on a fixed part of the machine and means for moving any selected one of said members, to the exclusion of the others, into the path of the device so as to operate the device and disengage the one-way clutch of the power drive upon the arrival of the selected magazine in operative position.

4. A typographical composing machine according to claim 3 including a cam for actuating the adjustable members and means for adjusting the cam to predetermined positions to move a pre-selected member into the path of the disconnecting device.

5. A typographical composing machine comprising a column of magazines, at least three in number, mounted on a bracket which is adjustable in opposite directions to bring a selected magazine into operative position, a uni-directional power drive, a cam which is rotatable in a single direction by said power drive, a cam lever connected to the magazine supporting bracket and operable by said cam for imparting a movement in opposite directions to the magazine column, a one-way clutch for connecting and disconnecting the magazine supporting bracket to and from the power drive, a tumbler mounted on the magazine supporting bracket and movable in opposite directions therewith and adapted to disconnect said clutch in any adjusted position of the magazine column, a plurality of adjustable members mounted on a fixed part of the machine, and means for moving any selected one of said members, to the exclusion of the others, into the path of the tumbler so as to move the tumbler and disconnect the clutch of the power drive upon the arrival of the selected magazine in operative position.

6. A typographical composing machine comprising a column of magazines, at least three in number, mounted on a bracket which is adjustable in opposite directions to bring a selected magazine into operative position, mechanism for effecting such adjustment of the magazine column including a rotatable shaft, a counterbalanced pulley fixed to said magazine adjusting shaft and to which the magazine supporting bracket is connected, said pulley being rotatable in opposite directions, a uni-directional power drive for said magazine adjusting mechanism, a one-way clutch for connecting and disconnecting the magazine adjusting mechanism to and from the power drive, a device mounted on the magazine supporting bracket and adapted to disengage the one-way clutch of the power drive, a plurality of adjustable members corresponding to the number of magazines in the column, said members being mounted on a fixed part of the machine, and means for moving any selected one of said members, to the exclusion of the others, into the path of the device so as to operate the device and disengage the one-way clutch of the power drive upon the arrival of the selected magazine in operative position.

7. A typographical composing machine according to claim 6 including mechanism for rotating the magazine adjusting shaft in one direction, mechanism for rotating the magazine adjusting shaft in the opposite direction, a two-way clutch which is connectible with either of said mechanisms, and means mounted on the magazine supporting bracket for effecting the automatic adjustment of said two-way clutch.

8. A typographical composing machine according to claim 7 including a cam for actuating the adjustable members, and means for adjusting the

cam to pre-determined positions to move a pre-selected member into the path of the disconnecting device.

5 9. A typographical composing machine comprising a column of magazines, at least three in number, which is adjustable in opposite directions to bring a selected magazine into operative position, mechanism for effecting such adjustment of the magazine column including a rotatable shaft, a magazine locator member fixed to said magazine adjusting shaft and rotatable in opposite directions during adjustment of the magazines, locator studs secured to said locator member, there being as many such studs as there are magazines in the column, an arm which is arranged to be engageable with any of said studs, means for moving said arm out of engagement with a locator stud to free the magazine column for adjustment, and means for moving the arm into engagement with any other stud to hold the magazine column in adjusted position.

10 10. A typographical composing machine comprising a column of magazines, at least three in number, which is adjustable in opposite directions to bring a selected magazine into operative position, mechanism for effecting such adjustment of the magazine column including a rotatable shaft, a pulley fixed to said magazine adjusting shaft and connected to a weight for counterbalancing the weight of the magazines, said pulley being rotatable in opposite directions to correspond with the adjustment of the magazine column, locator studs secured to said pulley, there being as many such studs as there are magazines in the column, an arm movably mounted on a fixed part of the machine adjacent said pulley, means for moving said arm out of engagement with a locator stud to free the magazine column for adjustment, and means for moving the arm into engagement with any other stud to hold the magazine column in adjusted position.

15 11. A typographical composing machine comprising a column of magazines, at least three in number, which is adjustable in opposite directions to bring a selected magazine into operative position, mechanism for effecting such adjustment of the magazine column including a rotatable shaft, a magazine locator member fixed to said magazine adjusting shaft and which is rotatable in opposite directions during adjustment of the magazines, a movable locator arm adapted to engage said magazine locator member to locate a selected magazine in operative position, a uni-directional power drive connected to the magazine adjusting mechanism for shifting the column of magazines in opposite directions, and means operable by movement of the locator arm for connecting and disconnecting the power drive.

20 12. A typographical composing machine comprising a column of magazines, at least three in number, which is adjustable in opposite directions to bring a selected magazine into operative position, mechanism for effecting such adjustment of the magazine column including a rotatable shaft, a pulley fixed to said magazine adjusting shaft and connected to a weight and adapted to counterbalance the weight of the magazines, a uni-directional power drive connected to the magazine adjusting mechanism to adjust the column of magazines in opposite directions, a movable locator arm for engaging said pulley to locate a selected magazine in operative position, and means operable by movement of the locator

arm for connecting and disconnecting the power drive.

13. A typographical composing machine according to claim 12 including pre-selecting means for engaging said locator arm with said pulley and disconnecting the power drive when a pre-selected magazine has been brought into operative position.

14. A typographical composing machine according to claim 13 including means connected to the column of magazines for rotating the pulley in opposite directions.

15. In a typographical composing machine, the combination of a column of magazines, at least three in number, adjustable in opposite directions to bring any selected one of the magazines into operative position, a continuously rotatable driving member, a periodically operated driven member rotatable in a single direction, a one-way clutch for coupling the driven member to the driving member, means operated by the driven member for adjusting the magazine column automatically in one direction or the other or in both directions during a given operation according to the position of a newly selected magazine in relation to the position of a previously selected magazine, means for engaging the clutch at will, automatic means for disengaging the clutch, and preselecting means for actuating said clutch disengaging means upon the arrival of the selected magazine in operative position regardless of the position of that magazine in the column and regardless of the direction in which the magazine column is adjusted.

16. The combination according to claim 15, wherein said pre-selecting means is settable at will in as many different operative positions as there are magazines in the adjustable column.

17. In a typographical composing machine, the combination of a column of magazines, at least three in number, adjustable in opposite direc-

tions to bring any selected one of the magazines into operative position, a continuously rotatable driving member, a periodically operated driven member rotatable in a single direction, a one-way clutch for coupling the driven member to the driving member, means operated by the driven member for adjusting the magazine column automatically in one direction or the other or in both directions during a given operation according to the position of a newly selected magazine in relation to the position of a previously selected magazine, means for engaging the clutch at will, automatic means for disengaging the clutch, including a device movable with the adjustable magazine column in either direction or in both directions according to the operation of the magazine adjusting means, a plurality of adjustable members corresponding to the number of magazines in the column and mounted on a fixed part of the machine, and manual means for setting any selected one of said members, to the exclusion of the others, into the path of the clutch disengaging device so as to actuate said device for the disengagement of the clutch upon the arrival of the selected magazine in operative position regardless of the position of that magazine in the column and regardless of the direction in which the magazine column is adjusted.

RICHARD HENRY SCOTT.
